POCKET TOOTHBRUSH

Theodore F. Jackson, Rockford, Ill., assignor, by
direct and mesne assignments, of one-half to
Walter B. Keres, Rockford, Ill.

Application August 12, 1946, Serial No. 690,036

9 Claims. (Cl. 132—84.2)

1

This invention relates to a new and improved pocket type toothbrush, the same being designed to be carried in the pocket like a fountain pen.

One of the principal objects of my invention is to provide a toothbrush of the kind mentioned having a tubular handle portion designed to receive a removable cartridge containing the dentifrice, such as tooth powder, the cartridge having a dispensing opening in one end which when the cartridge is in place in the handle is sealed by a conical projection provided in the inner end of the handle, whereby to prevent loss and waste of dentifrice, and give better sanitation.

Another object is to provide a toothbrush of the kind mentioned in which a cap threadedly engaged in the outer end of the handle of the toothbrush to retain the dentifrice cartridge contains a coiled compression spring or other suitable resilient compressible means which in the tightening of the cap applies yielding pressure to the outer end of the cartridge to hold it in its proper position without danger of crushing it or forcing the conical projection too firmly into the neck end.

Still another object is to provide a toothbrush of the latter description in which spring means is also provided in the inner end of the handle to assist in freeing the cartridge when the plug is removed from the outer end of the handle, thus facilitating use of the toothbrush.

The invention is illustrated in the accompanying drawing, in which

Fig. 1 is a side view of a toothbrush made in accordance with my invention showing the caps removed;

Fig. 2 is a side view of another toothbrush showing a modified or alternative construction in so far as the closure cap is concerned;

Fig. 3 is a sectional view of still another toothbrush showing another modified or alternative construction;

Figs. 4 and 5 are cross-sections through the bristle end of the brush, showing two different constructions, and

Fig. 6 is a side view of one of the dentifrice cartridges as it will be sold for use in either one of the three toothbrushes herein disclosed.

Similar reference numerals are applied to corresponding parts throughout the views.

Referring first to Fig. 1, the reference numeral 7 designates the head of the toothbrush on which the usual bristles 8 are provided, and 9 is the tubular handle in which a removable cartridge 10 containing the dentifrice such as tooth powder, is adapted to be entered, a cap 11 threadable

2

in the outer end of the handle serving to hold the cartridge 10 in place. A tubular cap 12 designed to fit over the head 7 and having a spring clip 13 thereon, similar to what are commonly provided on the caps of fountain pens, is arranged either to thread on the end of the handle 9 or have a tight friction fit thereon and is suitably provided with perforations 14 for ventilation to permit drying out of the bristles 8 when the cap 12 is in place after the brush has been used. The cap 12 is cylindrical, as shown in Fig. 4, when the head 7 is of the form shown in that figure and when the handle 9 is also of cylindrical form to have a friction fit or threaded fit in the cap. 5 However, I may provide a cap 12a of square or rectangular section, as shown in Fig. 5, when the head is of the rectangular form, indicated at 7a, and when the handle is of rectangular or square cross-section, and designed to have a wedging 10 friction fit in the cap. 15

In accordance with my invention, the cartridges 10 will be made of cardboard, plastic, or any other suitable stiff material and formed to provide a reduced neck portion 15 into which a 20 disposable plug 16 of wood, plastic, or other suitable material is fitted with a tight friction fit. This plug is removed and discarded when the cartridge 10 is to be inserted in the handle 9 or 9a and the cartridge is of such length in relation 25 to the length of the handle that the conical projection 17 in the center of the inner end of the handle has a tight wedging fit in the neck 15 to seal the cartridge against likelihood of leakage 30 of any dentifrice when the cap 11 has been threaded on the handle behind and in abutment 35 with the cartridge.

In operation, it is only necessary to remove the cap 12 from the head end of the brush and then unscrew the cap 11 from the outer end of the 40 handle in order to permit removal of the cartridge 10, whereupon the brush is ready for use when, for example, the powder is sprinkled onto the bristles or a given amount of the powder is poured into the palm of one hand and the wet 45 bristles are dipped in the powder. After the brush has been used and has been rinsed off, the cartridge 10 can be replaced and retained and sealed tightly by inserting and tightening the cap 11. Inasmuch as there is no opportunity for 50 the cartridge to move endwise there is no danger of any loss and waste of powder. The cap 12 may be replaced and the brush placed in the pocket without waiting for the bristles to dry, if the excess water is shaken off after the brush 55 has been rinsed.

If desired, I may, as shown in Fig. 2, provide a coiled compression spring 18 in a socket 19 in the cap 11a, the cap 11a being designed to thread into the open end of the handle 9 the same way as the cap 11. With this construction it is apparent that regardless of slight variation in the overall length of the cartridges 10 there will be no likelihood of any leakage of tooth powder, because the spring 18 will be compressed between the outer end of the cartridge 10 and the cap 11a in the threading of the cap in place, so that the cartridge is placed under a yielding pressure insuring good sealing engagement of the conical projection 17 in the neck end 15 of the cartridge. With this construction there is also assurance of reasonably good sealing of the cartridge even when the user fails to tighten the cap 11a as tightly as possible, because the spring 18 comes into contact with the end of the cartridge 10 as soon as the cap 11a is started in the outer end of the handle and the spring compresses more and more the farther the cap is tightened.

If desired, I may also provide, as shown in Fig. 3, still another coiled compression spring 20, lighter than the coiled compression spring 18 in the inner end of the handle 9a surrounding the conical projection 17a and arranged to have abutment with the inner end of the cartridge 10 and be compressed between the handle and the cartridge when the cap 11a is inserted and tightened. In that way, when the cap 11a is removed there is a sufficient pressure exerted on the inner end of the cartridge 10 to eject it, or at least help in its removal from the handle. Of course, it should also be evident that I may provide the spring 20 alone in combination with a plain closure cap like that shown at 11 in Fig. 1, so that the cartridge 10 is more or less positively seated by the cap against the projection 17 or 17a but is spring pressed in the outward direction for easier removal.

It is believed the foregoing description conveys a good understanding of the objects and advantages of my invention. The appended claims have been drawn to cover all legitimate modifications and adaptations.

I claim:

1. A toothbrush comprising a body providing a head portion having bristles projecting therefrom, and an elongated tubular handle portion extending from and rigid with the head portion, said handle portion being open at its outer end and closed at its inner end and having a substantially conical projection in that end, an elongated cartridge adapted to contain a dentifrice and having a dispensing opening in one end, the cartridge being slidable endwise in and removable endwise from the handle and disposed in said handle portion with the projection entered in and closing the dispensing opening, and means threaded on the open end of the handle against the end of the cartridge to retain said cartridge in said handle and cause the projection to be entered tightly in the dispensing opening.

2. A toothbrush comprising a body providing a head portion having bristles projecting therefrom, and an elongated tubular handle portion extending from and rigid with the head portion, said handle portion being open at its outer end and closed at its inner end and having a substantially conical projection in that end, a coiled compression spring seated in the closed inner end surrounding the conical projection, an elongated cartridge adapted to contain a dentifrice and having a dispensing opening in one end, the car-

tridge being disposed removably in said handle portion engaging said spring and with the projection entered in and closing the dispensing opening, the outer end portion of said handle being threaded, and a cap threaded on said handle so as to force the cartridge into the handle against the resistance of said spring in closer sealing engagement with said projection and retain the cartridge in the handle, said spring serving to assist removal of the cartridge when the cap is removed.

3. A toothbrush comprising a body providing a head portion having bristles projecting therefrom, and an elongated tubular handle portion extending from and rigid with the head portion, said handle portion being open at its outer end and closed at its inner end and having a substantially conical projection in that end, an elongated cartridge adapted to contain a dentifrice and having a dispensing opening in one end, the cartridge being disposed removably in said handle portion with the projection entered in and closing the dispensing opening, a coiled compression spring surrounding said conical projection and seated in the inner end of said handle and arranged to be compressed when the cartridge is moved inwardly to sealing engagement with said projection, whereby to urge the cartridge outwardly when it is desired to remove it, the outer end portion of said handle being threaded, a cap threaded on said handle so as to force the cartridge into the handle in closer sealing engagement with said projection and retain the cartridge in the handle, and a resilient member in the cap compressed between the cap and the outer end of the cartridge to press the open end of the cartridge resiliently into wedging sealing contact with said conical projection.

4. A toothbrush comprising a body providing a head portion having bristles projecting therefrom, and an elongated tubular handle portion extending from and rigid with the head portion, said handle portion being open at its outer end and closed at its inner end and having a substantially conical projection in that end, an elongated cartridge adapted to contain a dentifrice and having a dispensing opening in one end, the cartridge being disposed removably in said handle portion with the projection entered in and closing the dispensing opening, a relatively light spring means in said handle which is compressed when the cartridge is moved inwardly to sealing engagement with said projection, whereby to urge the cartridge outwardly when it is desired to remove it, the outer end portion of said handle being threaded, a cap threaded on said handle so as to force the cartridge into the handle in closer sealing engagement with said projection and retain the cartridge in the handle, and a second and relatively heavy spring means on said cap which in the application of the cap on the handle engages the outer end of the cartridge and is compressed when the cap is tightened whereby to urge the cartridge yielding inwardly against the action of the first spring means.

5. A toothbrush comprising a body providing a head portion having bristles projecting therefrom, and an elongated tubular handle portion extending from and rigid with the head portion, said handle portion being open at its outer end and closed at its inner end and having a substantially conical projection in that end, an elongated cartridge adapted to contain a dentifrice and having a dispensing opening in one end, the cartridge being slidable endwise in and remov-

able endwise from the handle and disposed in said handle portion so that the dispensing opening is closed by the conical projection in the closed inner end of the handle, a cap threaded on the open end of said handle to retain the cartridge in the handle, and a resilient member in the cap compressed between the cap and the outer end of the cartridge to press the open end of the cartridge resiliently into wedging sealing contact with said conical projection.

6. A toothbrush comprising a body providing a head portion having bristles projecting therefrom, and an elongated tubular handle portion extending from and rigid with the head portion, said handle portion being open at its outer end and closed at its inner end, an elongated cartridge adapted to contain a dentifrice and having a dispensing opening in one end, the cartridge being slidable endwise in and removable endwise from the handle and disposed in said handle portion so that the dispensing opening is closed by the closed inner end of the handle, the outer end portion of said handle being threaded, and a cap threaded on said handle so as to force the cartridge into the handle in closer sealing engagement with the closed inner end of said handle and retain the cartridge in the handle.

7. A toothbrush comprising a body providing a head portion having bristles projecting therefrom, and an elongated tubular handle portion extending from and rigid with the head portion, said handle portion being open at its outer end and closed at its inner end, an elongated cartridge adapted to contain a dentifrice and having a dispensing opening in one end, the cartridge being disposed removably in said handle portion so that the dispensing opening is closed by the closed inner end of the handle, spring means in said handle which is compressed when the cartridge in the handle is moved toward the closed end of the handle whereby to urge the cartridge outwardly when it is desired to remove it, the outer end portion of said handle being threaded, and a cap threaded on said handle so as to force the cartridge into the handle in closer sealing engagement with said projection and retain the cartridge in the handle.

8. A toothbrush comprising a body providing a head portion having bristles projecting therefrom, and an elongated tubular handle portion extending from and rigid with the head portion, said handle portion being open at its outer end and closed at its inner end, an elongated cartridge adapted to contain a dentifrice and having a dispensing opening in one end, the cartridge

being disposed removably in said handle portion so that the dispensing opening is closed by the closed inner end of the handle, spring means in said handle which is compressed when the cartridge in the handle is moved toward the closed end of the handle whereby to urge the cartridge outwardly when it is desired to remove it, the outer end portion of said handle being threaded, a cap threaded on said handle so as to force the

cartridge into the handle in closer sealing engagement with said projection and retain the cartridge in the handle, and a second spring means on said cap which in the application of the cap on the handle engages the outer end of the cartridge and is compressed when the cap is tightened, whereby to urge the cartridge yieldingly inwardly against the action of the first spring means.

9. A toothbrush comprising a body providing a head portion having bristles projecting therefrom, and an elongated tubular handle portion extending from and rigid with the head portion, said handle portion being open at its outer end and closed at its inner end, an elongated cartridge adapted to contain a dentifrice and having a dispensing opening in one end, the cartridge being disposed removably in said handle portion so that the dispensing opening is closed by the closed inner end of the handle, the outer end portion of said handle being threaded, a cap threaded on said handle so as to force the cartridge into the handle in closer sealing engagement with said projection and retain the cartridge in the handle, and spring means on said cap which in the application of the cap on the handle engages the outer end of the cartridge and is compressed when the cap is tightened, whereby to urge the cartridge yieldingly inwardly.
